IMAGE AMPLIFIER PHOTOTIMER

Benjamin De Witt, Baltimore, Md., assignor to Westinghouse Electric Corporation, East Pittsburgh, Pa., a corporation of Pennsylvania

Application August 16, 1951, Serial No. 242,141

6 Claims. (Cl. 250—65)

My invention relates to timing devices and in particular comprises an arrangement for timing the operation of a source of X-rays or other penetrating radiation in accordance with the amount of such radiation which has penetrated an object being irradiated. It is applied with particular advantage to X-ray apparatus which embodies an X-ray image intensifier such as that shown and described in Mason and Coltman, U. S. Patent No. 2,523,132.

It is becoming a more and more desirable practice in making X-ray examinations particularly in the medical field, to employ fluoroscopy that is, to view the image of the object being irradiated on a fluorescent screen. While it has been the practice for many years to follow this practice, great difficulty has always been experienced from the dimness of the fluorescent image, which has been so great that the observer has had to wait in a darkened room for periods of the order of thirty or forty minutes to adapt his eyes to the low light level he must work with. The above mentioned patent describes an image intensifier having a fluorescent screen at its input end and having an electron-phosphor screen at its output end on which an image of brightness something over one hundred times that on the fluorescent screen is produced. This arrangement has practically revolutionized X-ray technique and made fluoroscopic examinations much more useful than they have ever been before.

The great intensification of brightness achieved in this image intensifier is brought about by positioning a photo-electric screen close to the fluorescent screen, thereby producing an electron image which duplicates in space distribution the light image produced by the X-rays on the fluorescent screen, and accelerating this electron image into incidence on the electron-phosphor output screen. On the latter there is thus produced a light image of greatly intensified brightness, which may be viewed through a suitable light-optical system, or may be photographed, either still or motion, for permanent record.

As is well known the duration and intensity of the X-ray beam are limited to undesirably low values in medical work by the harmful effects of too great exposure of the patient to the rays. The use of other types of penetrating radiation than X-rays, for example, beams of neutrons, is also slowly coming into practice and is subject to similar limitations due to exposure danger. It is accordingly necessary to provide for terminating the irradiating beam after a predetermined amount of exposure to the radiation. This can be done automatically in the case of apparatus employing image intensifiers since the number of electrons which has been emitted from the photo-electric screen is directly proportional to the number of roentgens of X-rays to which the patient has been exposed at any time.

One object of my invention is accordingly to provide an improved X-ray apparatus in which a great increase is attained in the brightness of a fluorescent image while at the same time the dosage of X-rays to which the patient is exposed is terminated at a desired value.

2

Another object of my invention is to provide an improved image intensifier apparatus which automatically intensifies the brightness of the image on a fluorescent screen, and at the same time controls the agency producing the image in accordance with the time-integral of such intensity.

Another object is to provide an arrangement in which visible pictures are generated by penetrating radiation and in which the source of radiation is controlled in correspondence with the time interval of the radiation which has, at any instant, generated the picture.

Still another object of my invention is to provide an arrangement in which visible images, produced by penetrating radiation, are photographed and the photographing apparatus is controlled in accordance with the total amount of radiation which has been employed.

Yet another object of my invention is to provide an apparatus producing visible pictures through the employment of penetrating radiation which automatically initiates and terminates the flow of radiation from its source in correspondence with the total amount of radiation which has been employed in the picture.

A further object is to provide an X-ray apparatus for fluoroscopy, in which an image intensifier amplifies the brightness of the image on the fluorescent screen, with means for photography recording the image in which means the photographic exposure is automatically regulated to accord with the brightness of the picture being photographed.

Other objects of my invention will become apparent from reading the following description taken in connection with the drawing in which the single figure is a schematic representation of an X-ray system embodying an image intensifier and equipped with controls in accordance with the principles of my invention.

Referring in detail to the drawing, a source of penetrating radiation such as an X-ray tube 1 of any suitable type is positioned to transmit a beam of radiation through any desired object onto the input screen of an image intensifier 2, which is shown here for illustrative purposes as of the general type described in the above mentioned Mason and Coltman patent. This image intensifier 2 comprises an input screen 3 having a layer of fluorescent material such as zinc sulphide separated by thin glass from a screen of photo-electrically emissive material such as cesiated antimony. At the opposite end of the tube 2 is positioned an output screen 4 having a thin layer of an electron-phosphor which may be zinc cadmium sulphide. The tube 2 is highly evacuated and may be provided in the space between screens 3 and 4 with a suitable electron lens system described in more detail in the above mentioned patent. A suitable voltage source 9 having its negative terminal grounded impresses a high positive voltage on the screen 4.

As described in the above mentioned patent radiation transmitted from the source 1 through the object being examined strikes the fluorescent screen 3, thereby producing a light image which generates on the photo-electric screen immediately contiguous to it an electron image corresponding with it point by point over the area of the screen. The positive output screen 4 accelerates the electrons composing this image which are focused by the electron lens system to produce, upon impact with the electron phosphor layer, a light image which is a replica, to very much reduced dimensions, of the light image on the screen 3.

If it is desired this light image on screen 4 may be viewed through a suitable light-optical system, preferably a magnifying one, whereby a light image substantially like that on the input screen 3 except that its brightness has been greatly magnified may be seen by an observer. However for certain purposes it is frequently

desired to make a photographic record of the light image on the screen 4 and this may be done by suitably operating a camera 5 which is preferably provided with an electrically controlled shutter 6.

When the radiation source 1 is energized a flow of electrons will be initiated from the photo-electric surface on the input surface 3 to the output screen 4, thereby setting up a current flowing to ground through the voltage source connected to screen 4 and thence back to the input screen 3 through a resistor 7 and lead 8.

The X-ray source 1 is energized by a transformer 11 having a primary winding connected through the normally open contacts of a relay 12 to a suitable source 13 of alternating current voltage. The energizing winding of the relay 12 may be connected to the voltage source 13 through the normally closed contacts of a relay 14 and a hand switch 15. The energizing winding of relay 14 is connected in the main electrode circuits of a gas discharge tube 16 which is provided with a control electrode. The relay 14 and the tube 16 are shunted across a resistor 17 which is fed from the positive terminal of the direct current voltage source 18 through the normally open contact of a relay 19. The negative terminal of the voltage source 18 is grounded. The energizing winding of the relay 19 is connected through the hand switch 15 across the terminals of the voltage source 13.

The end of the resistor 17 which is remote from the normally open contact of the relay 19 is connected through a resistor 21 to the anode of a grid-controlled electron tube 22 which is here shown as a tetrode and also through a pair of resistors 23 and 24 to ground. The anode of the tetrode 22 is connected through a variable resistor 25 to the control electrode of the tube 16. The control grid of the tube 22 is connected to the ungrounded end of the resistor 7. A capacitor 26 is shunted between the control grid and the cathode of the tube 16, and is shunted by a pair of normally closed contacts on the relay 19. When it is desired to employ the automatic shutter 6 on the camera 5 it may be connected in shunt across the input terminals of the transformer 11.

The mode of operation of the above described system is as follows: When the hand switch 15 is closed current flows through it and the normally closed contacts of relay 14 to energize the relay 12 from the power source 13. Relay 12 energizes transformer 11 thereby causing a beam of X-rays from the source 1 to irradiate the input screen 3 of the image intensifier tube 2 after transmission through the object under observation. The light image thus generated on the screen 3 produces a corresponding electron image, the electrons of which flow through the tube 2 and the resistor 7 thereby producing a positive voltage on the control electrode of the tube 22, and at the same time producing a light image on the output screen 4.

It will be noted that the normally closed contacts of the relay 19 maintain a short circuit across the capacitor 26 until relay 19 is energized. When the hand switch 15 was closed as above described it energized the relay 19 to open this short circuit about the capacitor 26 and at the same time to close its normally open contacts thereby connecting the lower end of the resistor 17 to the positive terminal of the voltage source 18. As a result of the closure of these normally open contacts a positive potential is impressed on the anode of the tetrode 22 and current flows through the latter tube by way of the resistor 21 and its shunt path including resistor 25 and the capacitor 26 to the positive terminal of the source 18 by way of the resistor 17. The flow of this current through the capacitor 26 starts to build up a charge on it but it has sufficient capacity so that the control grid of the tube 16 is not immediately effective to start current flow between the main electrodes of the latter. Closure of the normally open contacts of the relay 19 also connected the upper electrode of the tube 16 through the energizing winding of the relay 14 across the potential drop due to

current in the resistor 17. Since the control electrode of the tube 16 was initially at the potential of its lower electrode that tube was non-conducting and no current flowed through the energizing winding of the relay 14.

5 However, sufficient voltage soon builds up on the capacitor 26 to initiate an arc discharge through the tube 16 whereupon the relay 14 is energized to open its closed contacts and thus interrupt current flow through the energizing winding of the relay 12. The contacts of the 10 latter then open to interrupt current flow from the source 13 to the X-ray tube 1 and to the shutter mechanism 6. Thus the X-ray beam from the tube 1 is cut off after a time fixed by the interval required by the capacitor 26 to charge up to a voltage sufficient to initiate current flow through the tube 16. The length of this interval can be set at any desired figure by adjusting the variable resistor 25.

The voltage drop through the resistor 7 is proportional to the intensity of the X-ray beam striking the fluorescent 20 screen of the image intensifier 2; and it is this voltage drop through the resistor 7 which determines the rate of current flow through tetrode 22 to charge the capacitor 26. The more intense the X-ray beam from source 1, the greater the current flow through tetrode 22 and the more rapidly will the capacitor 26 charge sufficiently to 25 initiate current flow through tube 16 thereby interrupting further flow of the X-ray beam. Thus the beam is interrupted when the time integral of its intensity reaches a predetermined figure, the latter being variable at will by adjusting the variable resistor 25.

Since the automatic shutter 6 is connected across the circuit supplying the transformer 11 it will be evident 30 that this shutter is opened when that transformer initiates the X-ray beam and is shut when the X-ray beam is interrupted. Thus the time integral of the light exposure of the film behind shutter 6 is likewise fixed at a predetermined value by the charging of the capacitor 26. While the contacts of relay 12 are shown as connected in series with both the transformer 11 and the shutter 6 35 it is believed to be obvious that they may be connected in either one of these circuits alone if control of the corresponding apparatus in accordance with the X-ray dosage should be desired.

After termination of the X-ray exposure by opening 40 of the contacts of relay 14, the relay 12 cannot be re-energized until the switch 15 has been opened. The opening of that switch deenergizes the energizing winding of relay 19 thereby opening its normally-open contacts to cut off current flow through resistors 17, 23 and 24, from the D. C. source 18. The gaseous discharge tube 16 is thus extinguished upon the cessation of current flow through resistor 17, permitting the normally closed contacts of relay 14 to close so that the energizing winding of relay 12 may be energized when manual switch 15 45 is next closed. At the same time that relay 19 is thus deenergized its normally closed contacts are shut and quickly dissipate the charge of capacitor 26. The system has thus been returned to the initial condition in which it stood at the time the foregoing operation cycle commenced.

50 While I have described my invention as used to administer a predetermined dosage of X-rays it will be evident that it may be employed to control in accordance with a predetermined time integral of radiation any type of apparatus for which such a regulation is desirable.

I claim as my invention:

55 1. In combination with a source of X-rays, an image intensifier including a photoelectric member to produce an electron space-image of an object irradiated by said source and an electron responsive fluorescent member spaced from said photoelectric member to generate a visible light image in response to impingement of said electron space-image, and means for controlling said source of X-rays including an electric circuit connected

to one of said members so as to be traversed by the electrons constituting said electron space-image.

2. In a fluoroscopic apparatus having a source of X-rays for producing an X-ray image of an object irradiated by said source, an image intensifier including a fluorescent screen responsive to said X-ray image, a photoelectric screen member positioned adjacent said fluorescent screen to produce a space distributed electron image having the pattern of said X-ray image, and an electron-phosphor screen member spaced from said photoelectric screen member for receiving said electron image to produce an intensified visible light image, and an electric circuit connected to one of said members for controlling said source to limit the duration of said X-ray image, said electric circuit including first circuit means traversed by electrons forming said image and second circuit means connected between said first circuit means and said source to control said source in response to the passage of a predetermined number of electrons through said first circuit means.

3. In combination with a fluoroscopic apparatus including a source of penetrating radiation, an image intensifier including a photoelectric member to produce an electron space-image of an object irradiated by said source and an electron-phosphor member spaced from said photoelectric member to produce a visible image in response to impingement of said electron space image thereon, and an electric circuit for controlling said source including circuit means connected to one of said members and traversed by electrons forming part of said space-image.

4. In combination with a fluoroscopic apparatus including a source of penetrating radiation to produce a radiation image of an object, an image intensifier including a photoelectric member to produce an electron image having the pattern of said radiation image and an electron phosphor member spaced from said photoelectric member to produce a visible light image in response to impingement of said electron image, photographic apparatus for recording said light image, and an electric circuit including circuit means connected to one of said members and traversed by electrons constituting said electron

image with said electric circuit being connected to said photographic apparatus to interrupt the operation thereof in response to the passage of a predetermined number of electrons through said circuit means.

5. Apparatus for making photographs comprising an image amplifier for converting an X-ray image into a light image including a photo-cathode and an anode, a source of potential coupled to said cathode and anode, a camera including film optically coupled to said image amplifier for photographing said light image produced thereby, and means coupled to said source and responsive to the current flow between said cathode and anode for controlling the correct exposure of said film.

6. Apparatus for making photographs comprising an image amplifier including a photo-cathode and an anode for converting an X-ray image into a light image, a source of potential coupled to said cathode and anode, a camera including film optically coupled to said image amplifier for photographing the light image produced thereby, and means coupled to said source and responsive to the current flow between said cathode and anode for controlling the correct exposure of said film, said means including a capacitor arranged to be charged by said anode-cathode current, and means responsive to the voltage across said capacitor to terminate the X-ray image to thereby stop further exposure of the film.
